PHOTOELECTRIC SOUND APPARATUS

Henry G. Weiss, Cincinnati, Ohio

Application April 23, 1934, Serial No. 721,975

10 Claims. (Cl. 179—100.3)

This invention relates to photo-electric sound apparatus such as forms part of various known means for recording and reproducing sound recordings by the use of linear phonogram carriers, for example film strips and other forms of tapes or ribbons.

An object of the invention is to provide a novel, simple, and inexpensive form of means for exciting a photo-electric cell in connection with sound recording or reproducing apparatus.

Another object of the invention is to provide an exciting means of the above character wherein is obviated the use of expensive lenses and lamps.

Another object of the invention is to provide means of the character stated, which, after an initial adjustment, requires no periodic adjustments during use, this feature being characteristic and rendering the device distinctively different from devices heretofore known and used for the same purpose.

A further object of the invention is to provide a device of the character stated, which may readily be installed on existing motion picture apparatus.

25 The foregoing and other objects are attained by the means described herein and disclosed in the accompanying drawings, in which:

Fig. 1 is a fragmental elevational view of a motion picture projecting machine embodying the 20 device of the invention enclosed within a casing.

Fig. 2 is a front elevational view of the device of invention, the casing being removed.

Fig. 3 is a side elevational view of the Fig. 2 device.

35 Fig. 4 is a top plan view of the device.

Fig. 5 is a cross-sectional view taken on line 30 5—5 of Fig. 3.

Fig. 6 is a cross-sectional view taken on line 6—6 of Fig. 2.

40 It is known to be common practice to equip motion picture projecting machines with sound reproducing apparatus comprising a photo-electric cell and associated means for setting up electrical currents corresponding, in frequency variations, with light acoustically modulated by reason of its passage through the sound recording portion of a translucent film.

45 The sound area of the film ordinarily is produced by photographic recordation, and the light rays to be modulated emanate from a low-voltage high-amperage exciter lamp positioned to project a narrow beam, in the form of a slit, through the film record and onto the anode of a photo-electric cell, to produce varying electrical currents which are then transformed into sound waves by the use of means including a loud speaker or sound amplifier.

Heretofore, the means for condensing the exciter lamp rays and projecting them as a narrow slit upon the film, required the use of expensive

lenses and complicated expensive means for adjusting the size of the slit as the filament of the lamp sagged or changed its relationship to the lenses. It was necessary, also, to use a high amperage lamp, which was necessarily short-lived 5 on account of the large current flow through the filament thereof. As the filament of the lamp gradually broke down or weakened due to the high current consumption, the position and the size of the light slit changed, resulting in poor reproduction of the recorded sound. In the prior devices, the latter condition was overcome by providing the complicated adjustments above referred to. The adjustments had to be effected frequently during the life of the exciter lamp, 10 and the quality of the sound produced was therefore dependent upon the skill of the person making the adjustments, and upon the appreciation of sound quality possessed by such person. For these reasons, and perhaps others, it was difficult 15 to secure and maintain a perfect reproduction of sound recordations carried by the film. All of the foregoing disadvantages and objectionable features of the prior devices have been overcome by means of the device of this invention, a detailed description of which follows.

Fig. 1 discloses a conventional motion picture projector, which includes a head 7 which includes the usual projecting lens structure 8 and means for moving the strip of motion picture film 30 9 past the projecting means. The film ordinarily is paid out from an upper reel 10, and passes between suitable guide rolls 12 onto a driving sprocket 13. The character 14 indicates an intermittently driven sprocket which performs to 35 move the film through the film gate member 15 with a uniform jerky motion. The film passes from the intermittent sprocket 14 onto and over a smoothly rotating sprocket 16, whence the film is pulled past a suitable shield or film support 17 by means of the smoothly rotating sprocket 18. From the sprocket 18 the film is guided downwardly, as at 19, to a receiving reel (not shown). The device of the present invention is shown within the broken away area 20 of Fig. 1, wherein 40 21 indicates a conventional photo-electric cell having an anode 22 and a cathode 23. Light rays from an exciter lamp 24 encased within the device of the invention are projected from a barrel or tube 25 onto the film at a point of 45 translation indicated at 26, and light, as modulated by the record markings on the film, passes through an opening 27 in the support member 17 and plays upon the anode 22 of the photo-electric cell.

50 The device comprising the lamp 24 and barrel 25 is shown in detail in the remaining drawing views. Said device may comprise a base member 28 upon which is fixedly mounted a pair of uprights or guide members 29 and 30 having 55

guide means 31 for supporting a condenser frame, or prism frame 32. The frame 32 fits snugly between the upright supports, and may be adjusted vertically by the use of any suitable means, there being shown a simple means for the purpose, in the form of an adjusting screw 33. Said screw may be rotatably supported within a cross member 34 and have threaded engagement with an aperture 35 in a cross member 36 of the prism frame. A second cross member 37 may be provided at the opposite end of said frame to maintain the frame in a rigid condition.

The frame is adapted to carry a plurality of multiple faced prisms or condenser elements 37 and 38, said elements being preferably though not necessarily adjustable for rotation in suitable bores 39 and 40 of frame 32. Any acceptable or suitable means may be provided for adjusting the prisms about their major axes, there being shown a friction means in the form of end caps 41, 42, 43 and 44, which may be cemented or otherwise secured to the end portions of the prisms. The end caps 43 and 44 may be provided with shafts or extensions 45 and 46 respectively, which may be slotted or otherwise formed at their ends for reception of a tool whereby the prisms may be rotated relatively. The shafts 45 and 46 may be rendered semi-accessible through an elongated perforation 47 provided in one of the uprights, such as 29. The prisms preferably are slightly spaced apart in a vertical plane, and directly behind their line of separation is mounted a plate 48 having an aperture 49 therein through which may pass a portion of the light rays projected from the exciter lamp 24. Due to the provision of a plurality of substantially flat faces on the prisms, the prisms may be rotated relatively until the light rays from the exciter lamp are condensed and projected forwardly toward the barrel 25 as an intense narrow beam, which may be further narrowed and restricted by means of the pair of slit-determining plates 50 and 51 which are securely mounted upon the forward end of the barrel or tube 26. One or both of the said plates may have a narrow slot 52 filed or otherwise formed in the knife edges 53 of the plates. The barrel or tube 25 preferably is made slightly adjustable axially by the use of any suitable means, such as relatively fine threads 54 which engage corresponding threads formed in the barrel supporting plate 55. The plate 55 may be suitably secured to the base 28.

Any suitable means may be provided for supporting the exciter lamp 24 behind the apertured plate 48 in position to project its rays therethrough. Said means may comprise a support 56 mounted upon the base plate 28, said support carrying a lamp socket 57 suitably proportioned so as to dispose the filament 58 of the exciter lamp directly behind the aperture 49. The lamp may be securely held within the socket in any suitable manner, such as by means of a screw 59. With the construction described herein, the lamp 24 may be operated on low amperage current, there being shown a six-volt two-candle-power lamp which has been found to operate satisfactorily. The device has been found so efficient that it is possible to use an ordinary flash light bulb in place of the six-volt lamp. As is clearly shown in Fig. 1, the entire assembly shown in Figs. 2, 3 and 4, is enclosed within a case or housing 60 which preferably is substantially light-tight.

75 To preclude undesirable reflections which

might interfere with securing a fine line of light at the sound record portion of the film, it has been found desirable to blacken the interior of the barrel 25, and also the inner face of the apertured plate 48. It is to be understood that after initial adjustment of the prisms and of the screw 33 which elevates and lowers the prism frame, there is thereafter no reason for disturbing the adjustments, and accordingly, the frictional supports for the prisms are made with as tight a fit as possible and the adjustment means 45 and 46, as well as adjustment screw 33, are completely enclosed within the case or cover 60. It has been found that the effectiveness of the structure illustrated and described is unaffected by any sagging or slight change in the position of the exciter lamp filament, such changes being effectively overcome automatically by the refractory angular faces of the prisms. In the embodiment illustrated herein, prisms having seven faces were employed, but satisfactory results can be secured by the use of multiple faced prisms of other types. The device, as will be observed, is not only inexpensive to manufacture but also inexpensive to operate, and the quality of the sound produced is in no wise dependent upon the skill or the appreciation of sound quality possessed by an operator. The device is properly adjusted when manufactured, or when installed, and requires no subsequent change in adjustment. The prisms employed in the device can be manufactured at a fraction of the cost of lenses which have been used heretofore. As indicated in Fig. 1, the device may be supported upon a suitable shelf 61 carried by the head of the projector.

The device of this invention is of course applicable to sound recording apparatus as well as sound reproduction apparatus.

It is to be understood that various modifications and changes in the structural details of the device may be made, within the scope of the appended claims, without departing from the spirit of the invention.

What is claimed is:

1. An apparatus for reproducing speech, music or the like sounds from vibrations recorded on a film, which apparatus comprises a photo-electric cell, means for imparting to the film a rapid linear movement past said cell, an exciter lamp and prism means for condensing the rays from said lamp and for initially projecting the condensed rays in line formation, means near the film for finally determining the dimensions of the condensed light projection prior to passage thereof through the film and onto the photo-electric cell, means enclosing the exciter lamp to preclude passage of stray light rays to said cell, and means intermediate the exciter lamp and the prism means for intercepting some of the lamp rays and directing others to a predetermined area of the prism means.

2. An apparatus for translating sound vibrations representative of speech, music and the like to or from a film record, which apparatus comprises a photo-electric cell, means for imparting to the film a rapid linear movement past said cell, an encased low-voltage low-amperage exciter lamp for said cell, prism means for condensing only a small proportion of the rays from said lamp and for initially directing the condensed light in line formation, and means adjacent to the film for finally determining the dimensions of the condensed light projection prior to passage thereof through the film and onto the photo-electric cell.

3. An apparatus for translating sound vibrations representative of speed, music and the like to or from a record carrier, which apparatus comprises a photo-electric cell, a low-voltage low-amperage exciter lamp of low intensity for said cell, prism means for condensing the rays from said lamp and for initially directing the condensed light in line formation, means adjacent to the carrier for finally determining the dimensions of the condensed light projection prior to passage thereof through the carrier and onto the photo-electric cell, means for varying the spacing between said last mentioned means and the prism means, an apertured plate for intercepting a pre-determined portion of the light rays directed toward the prism means by the lamp, and means for moving the record carrier relative to the projected line of light.

4. In an apparatus of the class described, the combination of a base, a frame supported by the base, a plurality of relatively adjusted longitudinal prisms supported by the frame in slightly spaced substantially parallel relationship, a barrel extended forwardly of and an apertured plate at the rear of the prisms, a source of light behind the aperture of the plate, the intensity of the light and the size of the aperture being coordinated to produce a desired projection and means associated with the barrel to limit egress of light rays condensed into line formation and projected into the barrel by said prisms.

5. In an apparatus of the class described, the combination of a base, a frame supported by the base, a plurality of longitudinal prisms supported by the frame in slightly spaced substantially parallel relationship, a barrel extended forwardly and an apertured plate extended rearwardly of the prisms, an exciter lamp behind the aperture of the plate, and means associated with the barrel to limit egress of light rays condensed into line formation and projected into the barrel by said prisms, the barrel, the plate aperture, the light source, and the slight space between the prisms being in alignment.

6. In an apparatus of the class described, the combination of a base, a frame supported by the base, a plurality of relatively adjusted longitudinal prisms supported by the frame in slightly spaced substantially parallel relationship, a forwardly extended barrel at one side and an apertured plate at the opposite side of the prisms, a source of light behind the aperture of the plate, and means associated with the barrel to limit egress of light rays condensed into line formation and projected into the barrel by said prisms, the barrel, the plate aperture, the light source, and the slight space between the prisms being in alignment, and means for confining the direct rays of the light source to one face of the plate, its aperture, and so much of the prisms as is exposed through the aperture.

7. In an apparatus of the class described, the combination of a base, a frame supported by the base, a plurality of longitudinal flat-faced prisms supported by the frame, the faces of which extend in a common direction longitudinally of the prisms, adjustment means for rotatably supporting the prisms in spaced substantially parallel relationship to provide for varying the angular relationship of the faces of one prism to the faces of the other prism, a source of light behind the

prisms, means for adjusting the prisms in unison relative to the source of light, a barrel disposed forwardly of the prisms transversely thereof, means for precluding forward projection of light rays otherwise than through the barrel, and means carried by the barrel for limiting the projection of light rays through the barrel.

8. In an apparatus of the class described, the combination of a base, a frame supported by the base, a plurality of longitudinal flat-faced prisms supported by the frame, the faces of which extend in a common direction longitudinally of the prisms, adjustment means for rotatably supporting the prisms in spaced substantially parallel relationship to provide for varying the angular relationship of the faces of one prism to the faces of the other prism, a source of light behind the prisms, means for adjusting the prisms in unison relative to the source of light, a barrel disposed forwardly of the prisms transversely thereof, means for precluding forward projection of light rays otherwise than through the barrel, and means carried by the barrel for limiting to a narrow fine line the projection of light rays through the barrel.

9. In an apparatus of the class described, the combination of a base, a frame supported by the base, a plurality of longitudinal flat-faced prisms the faces of which extend in a common direction longitudinally of the prisms, means on the frame for supporting the prisms in closely spaced substantially parallel relationship with their faces disposed in proper relationship to project a condensed narrow line of light when light rays are directed onto the prisms, a source of light behind and adjacent to the prisms, an apertured plate intermediate the light source and the prisms for limiting application of light to the prisms over a restricted area, a barrel disposed forwardly of the prisms transversely thereof, means for precluding forward projection of light from the prisms otherwise than through the barrel, and means including a narrow slit in substantially the plane of the condensed narrow line of light, for limiting passage of the light rays through the barrel.

10. In an apparatus of the class described, the combination of a base, a frame supported by the base, a plurality of longitudinal flat-faced prisms the faces of which extend in a common direction longitudinally of the prisms, means on the frame for supporting the prisms in closely spaced substantially parallel relationship with their faces disposed in proper relationship to project a condensed narrow line of light when light rays are directed onto the prisms, a source of light behind and adjacent to the prisms, an apertured plate intermediate the light source and the prisms for limiting application of light to the prisms over a restricted area, a barrel disposed forwardly of the prisms transversely thereof, means for precluding forward projection of light from the prisms otherwise than through the barrel, means including a narrow slit in substantially the plane of the condensed narrow line of light, for limiting passage of the light rays through the barrel, and a photo-electric cell having light responsive means supported in the path of said condensed narrow line of light.

CERTIFICATE OF CORRECTION.

Patent No. 2,079,537.

May 4, 1937.

HENRY G. WEISS.

It is hereby certified that error appears in the printed specification of the above numbered patent requiring correction as follows: Page 3, first column, line 2, claim 3, for "speed" read speech; and that the said Letters Patent should be read with this correction therein that the same may conform to the record of the case in the Patent Office.

Signed and sealed this 29th day of June, A. D. 1937.

(Seal)

Henry Van Arsdale
Acting Commissioner of Patents.
